Attorney

UNITED STATES PATENT OFFICE.

JOHN M. PARKER, OF GOODMAN, MISSOURI.

COMBINED MANGER AND TROUGH.

Application filed December 19, 1925. Serial No. 76,482.

To all whom it may concern:

Be it known, that I, JOHN M. PARKER, a citizen of the United States, residing at Goodman, in the county of McDonald and State of Missouri, have invented certain new and useful Improvements in a Combined Manger and Trough, of which the following is a specification.

The present invention relates to improvements in animal feeding devices, and is more particularly adapted to a combined manger and feed trough.

One of the important objects of the present invention is to provide a manger and trough construction wherein the latter may be readily moved into an operative or inoperative position with respect to the manger.

A further object is to provide a device of the above mentioned character wherein means is provided for supporting the hinged feed trough in a horizontal position when the same has been swung inwardly into the manger. Additional means is also provided for securing the feed trough in its inoperative position so that the animals may obtain ready access to the hay within the manger.

A further object is to provide a device of the above mentioned character which is simple in construction, inexpensive, strong and durable and further well adapted to the purpose for which it is designed.

Other objects and advantages of the invention will become apparent during the course of the following description taken in connection with the accompanying drawings.

In the accompanying drawings forming a part of this application and in which like numerals designate like parts throughout the same:

Figure 1 is a rear elevation of the device showing the feed trough in its operative position within the manger.

Figure 2 is a top plan view thereof.

Figure 3 is a fragmentary sectional view taken approximately on line 3—3 of Figure 1.

Figure 4 is a view similar to Figure 1 showing the feed trough in its inoperative position.

Figure 5 is a top plan view thereof, and Figure 6 is a vertical sectional view

through the manger, and the feed trough, 55 with the latter being in its inoperative position.

In the drawing wherein for the purpose of illustration is shown the preferred embodiment of my invention, the numeral 1 60 designates generally the manger, the same comprising the front wall 2, the rear wall 3, and the end walls 4. The rear wall 4 is of relatively short height as is clearly illustrated in the several figures of the 65 drawings, and the purpose thereof will hereinafter be more fully described.

The front wall is provided with a vertically extending face or opening 5 and adapted for cooperation therewith are the stanchions 6.

The lower ends of these stanchions are pivotally secured between the inner and outer longitudinally extending strips 7 and 8 respectively as indicated at 9, the upper ends of these stanchions extending upwardly between the upper longitudinally arranged inner and outer strips 10 and 11 respectively. These pivoted stanchions cooperate with the adjacent side edges of the openings 75 formed in the front wall of the manger in holding the head of the animal within the manger in the manner well known in the art.

Secured to the inner side of the rear wall 3 of the manger 1 are a pair of brackets 12, 85 the same being arranged adjacent the respective ends of the manger. Each of the brackets has its upper end bifurcated as illustrated at 13 and pivotally secured at its outer end in each of the bifurcated upper 90 ends of the respective brackets is the arm 14, the pivotal connection therefor being illustrated at 15.

A feed trough designated generally by the numeral 16 and being divided into a number of compartments through the medium of the transverse partitions 17 extends across these arms and being secured thereto in any suitable manner so as to swing 95 with the arms to an operative or inoperative position in the manner to be presently described. As is clearly shown in the drawings, the free ends of the arms extend beyond the adjacent side of the feed trough.

An apron 18 extends upwardly at an incline from the rear side of the trough 16, and this apron is attached to a pair of arms such as are shown at 19, the latter being 100 105

hingedly secured to suitable brackets attached to the rear side of the trough, indicated by the numeral 20, the pivotal connection being shown at 21. A pair of leg members 22 are pivotally secured to the outer ends of the arms 19, and the lower end of each of the leg members is bifurcated so as to be removably disposed over the pins 23 which extend transversely in suitable notches 24 provided in the upper edge of the rear wall 3 of the manger 1.

When the leg members 22 are disposed in the position shown in Figure 3 of the drawings, the apron 18 will be supported at its 15 properly inclined position with respect to the rear side of the feed trough 16 so that the waste of the feed will be prevented.

For the purpose of supporting the feed trough in a horizontal position when the 20 same is swung inwardly into the manger so that the animals may obtain the food or water within the trough, there is provided on the inner side of the front wall 2 of the manger a stop or shoulder 25, and the 25 forward free ends of the arms 14 which carry the trough rest on the respective shoulders or stops.

When the trough is disposed in a horizontal position within the manger 1, access 30 to the hay or other loose feed placed in the manger cannot be obtained by the animals whose heads extend into the manger through the front wall thereof. In order to permit the animals to obtain the material in the 35 bottom of the manger, the leg members 22 are raised upwardly so as to become disengaged from the pins 23, and then the arms 14 carrying the trough 16 are swung upwardly on the pivots 15, the notches 24 permitting 40 the brackets 20 to extend therethrough in order that the rear side of the trough will rest on the upper edge of the rear wall 3 of the manger in the manner as clearly shown in Figure 6. For the purpose of holding the 45 trough in its raised inoperative position so as to be clear of the inside of the manger, I provide a pair of looped members 26, the same being pivotally supported on the upper ends of the posts 27 formed at the 50 upper rear corners of the respective ends of the manger 1. These posts 27 are formed by cutting away the upper rear portions of the end walls 4 of the manger 1 as at 28 with reference more particularly to Figure 55 6. The free ends of the looped members 26 are adapted to swing over and engage the free ends of the pivoted arms 14 when the latter are disposed in a vertical plane, thus locking the arms and the trough carried 60 thereby against swinging movement in either direction.

The provision of a combined manger and feeding trough construction of the above 65 mentioned character enables either of the devices to be used for feeding purposes, and

furthermore the trough may be readily and easily moved to an operative or inoperative position as may be desired.

By also arranging the trough on the rear wall of the manger in the manner as heretofore described, the manger may be easily cleaned when the trough is disposed in an upright inoperative position. Also, the provision of the apron at the rear side of the trough will prevent other waste of the feed 75 when the trough is in an operative position.

While I have shown the preferred embodiment of my invention, it is to be understood that minor changes in the size, shape and arrangement of parts may be resorted to without departing from the spirit of the invention and the scope of the appended claims.

Having thus described the invention, what I claim as new and desire to secure by Letters Patent is:—

1. In combination, a manger including front, rear, and end walls, the front wall being provided with openings through which the heads of the animals extend, stanchions cooperating with the openings, the rear wall being of a shorter height than the front wall, a feed trough, a pair of arms secured to the under side of the trough, the rear ends of the arms being pivotally associated with the inner side of the rear wall of the manger, the forward ends of the arms projecting beyond the forward side of the trough, and stops arranged on the inner side of the front wall of the manger, and cooperating with the forward ends of said arms for supporting the trough in a horizontal position when the latter is swung inwardly in the manger.

2. In combination, a manger including front, rear, and end walls, the front wall being provided with openings through which the heads of the animals extend, stanchions cooperating with the openings, the rear wall being of a shorter height than the front wall, a feed trough, a pair of arms secured to the under side of the trough, the rear ends of the arms being pivotally associated with the inner side of the rear wall of the manger, the forward ends of the arms projecting beyond the forward side of the trough, and stops arranged on the inner side of the front wall of the manger, cooperating with the forward ends of said arms for supporting the trough in a horizontal position when the latter is swung inwardly in the manger, said trough adapted to be swung upwardly to an inoperative position when the rear side of the trough engages the upper edge of the rear wall of the manger, and means for holding the trough in its vertical inoperative position.

3. In combination, a manger including front, rear, and end walls, the front wall being provided with openings through which

the heads of the animals extend, stanchions cooperating with the openings, the rear wall being of a shorter height than the front wall, a feed trough, a pair of arms secured to the under side of the trough, the rear ends of the arms being pivotally associated with the inner side of the rear wall of the manger, the forward ends of the arms projecting beyond the forward side of the trough, and stops arranged on the inner side of the front wall of the manger, cooperating with the forward ends of said arms for supporting the trough in a horizontal position when the latter is swung inwardly in the manger, said trough adapted to be swung

upwardly to an inoperative position when the rear side of the trough engages the upper edge of the rear wall of the manger, means for holding the trough in the vertical inoperative position, said last mentioned means comprising a pair of pivoted looped members associated with the upper rear portions of the respective end walls of the manger, and adapted to extend over the forward free ends of the arms when the latter are disposed in a vertical position.

In testimony whereof I affix my signature.

JOHN M. PARKER.
